UNITED STATES PATENT OFFICE

CHARLES WARD HALL, OF LARCHMONT, NEW YORK

RIVETED JOINT

Application filed March 26, 1925. Serial No. 18,542.

The forms of riveted joints have long been standardized, and in all of them the material, proportions and pitch of the rivets, which are subjected chiefly to shearing stress, are determined according to well-established specifications. The rated efficiency of the various forms of the joints ranges all the way from a minimum of about 50 per cent., for a single-riveted lap-joint, to 94 per cent. 10 in the case of a quadruple-riveted butt-joint, the utmost attainable in lap-joints being 67 per cent.

The object of my present invention is to improve upon the established practice in 15 joints of this type and, by increasing their efficiency, to reduce both the weight and the cost of the jointed structure.

To this end the invention consists, briefly, in forming the rivet-holes in the bottoms of 20 conical offsets or countersinks stamped in the plates, and to rivet together the two plates with the projections on one nested within the depressions in the other.

In the joint thus formed the shearing stress 25 is practically all transferred from the rivets to the flanged edges of the holes, while the rivets are subjected to little if any additional longitudinal tension in holding the plates clamped together. As a result, the sectional 30 area of the rivets required for a given joint being reduced, either smaller rivets may be used or, as is preferable, they may be given a greater pitch or be arranged in fewer rows. Furthermore, I am able not only to produce 35 lap-joints of 100 per cent. efficiency but joints presenting a smooth surface on one side due to the countersinking of the rivet heads in the depressions in one of the two plates, a result which in the case of very thin plates or 40 sheets could not otherwise be obtained.

Several forms of my improved joint are shown, by way of illustration and not of limitation, in the accompanying drawings, in which—

and 5 are views, corresponding to Figs. 1 and 2, of a triple-riveted lap-joint; Fig. 6 is a perspective view of one of the rivet cover caps shown in Fig. 4; and Fig. 7 is a perspective view of a broken length of spiral riveted pipe 55 showing the application thereto of a single-riveted lap-joint embodying my improvements.

Referring first to Figs. 1 and 2, *a* and *b* indicate the two plates, or plate sections, and *c* 80 indicates a cover strap used in connection with the inner of the two rows of rivets *d* and *e*, by which the plates are joined. The rivets of the inner row are set in holes *d*¹ formed in the bottoms of the conical offsets 65 or countersinks *a*¹, *b*¹ and *c*¹ which are stamped out in the respective plates and form as it were conical flanges around the rivet-holes, and in which are nested the projections of the lower plate within the the depressions 70 formed in the upper plate and the projections of this upper plate within the depressions formed in the cover. The rivets of the outer row are similarly set in holes *e*¹ formed in the bottoms of a second row of conical offsets or 75 countersinks *a*² *b*², which are formed and nested together in the same way. In both rows the headed ends of the rivets are countersunk in the conical depressions formed in the lower side of the bottom plate. 80

As a matter of practice, the offsets and concentric rivet holes will usually be punched in both plates, and in the cover, at a single operation in a suitable press, which should form the offsets slightly in advance of the rivet-holes since, if the rivet-holes are formed first, the off-sets will be split around the edges of the holes and so weakened. A depth for the conical depressions of from two to three times the thickness of a plate will be found to give satisfactory results and is recommended. The size and pitch of the rivets, and hence of the rivet-holes, will depend largely upon the angle which is given to the conical depressions and projections formed in the plate around the holes. Inasmuch as the smaller this angle the less the force required to maintain the joint, as the angle decreases and the walls of the offsets approach parallelism the smaller will be the 95 100

diameter of the rivets which may be used or the greater the pitch at which they are set. As a rule the walls may satisfactorily have a conical angle of from 80 to 50 degrees where the plates are of fairly ductile material, or, in very ductile material such for instance as duralumin immediately after quenching or soft annealed steel, may be nearly parallel.

For plates of less ductility the angle will usually vary from the neighborhood of 80 up to about 110 degrees. A preferred way of determining the most economical riveting

for plates of non-standardized material is to test their ductility for the offsetting operation by successive trials and to adopt the offsets with the steepest sides, or having the smallest conical angle, to which the material can be formed without developing incipient cracks. As the angle approaches zero and the

walls parallelism, the outer end or tip of the body of the punch should be of one-fourth to one-half larger diameter than the rivets so as to form at the bottom of the depressions an annular projection or shoulder around the rivet-hole over which to upset the rivet-head.

In the joint here illustrated, the angle α of the conical walls of the depressions and offsets is 72 degrees, and the rivets, of a diameter equal to two and one-half times the thickness of each plate, have a long pitch and a short pitch respectively of five and three times such diameter. This joint, with rivets of the same material as the plates, has a 100 per cent. efficiency, or, without the cover strap shown, an efficiency of 76 per cent.; whereas, the specifications for a standard double-riveted lap-joint, in which as stated the highest efficiency attainable is 67 per cent., call for rivets of a diameter two and three-fourths to three times the plate thickness and set at a long pitch of only three and one-fourth diameters. I therefore obtain with less than two-thirds the number and sectional area of rivets a joint of greater efficiency than that heretofore attainable.

In the modified joint shown in Fig. 3, the conical offsets a^1 and b^1 around the inner row of rivet holes are reversed, being punched out from the upper to the lower sides of the plates so as to project in the opposite direction to the offsets a^2 and b^2 of the outer row, and the rivets d used therein are countersink, instead of button-head, rivets. By this modification I obtain, without the aid of any cover strap, a joint of 100 per cent. efficiency.

In the triple-riveted lap-joint of Figs. 4 and 5, the angle α^1 of the conical offsets a^1 , a^2 , a^3 , etc., around the rivet holes is shown as of 90 degrees, and the rivets have, as shown, a diameter equal to three times the plate thickness. The short pitch of the three rows of rivets d , e and f is four times the rivet diameter, while the long pitch of the rivets is the same in the middle row and twice as great, or

eight times the rivet diameter, in the inner and outer rows. Individual cover caps c^2 , with conical offsets c^3 , are here used in connection with the inner row of rivets in place of the continuous cover strap shown in the double-riveted joint already described. Here again the joint produced has an efficiency of 100 per cent.

For spiral pipe, where as is well known the strain upon the rivets is much less than in pipe with longitudinal riveted joints, the single-riveted joint illustrated in Fig. 7, with rivets d set in holes surrounded by nested offsets b^5 in the overlapped edges a^4 , b^4 of the spiral plate, produces a pipe of high strength, to approach which a double-riveted joint would be required according to the present standard practice.

It will of course be understood that the invention is applicable to butt-joints as well as to lap-joints, and that the details of the joint may be variously modified without departing from the spirit or sacrificing the substantial advantages thereof—for instance, while a circular conic frustum is shown as a convenient form for the offsets, they may have other than circular sections and may also be inclined so as to present a more nearly perpendicular face on one side than on the other.

What I claim as new, and desire to secure by Letters Patent, is—

1. In a joint of the type described, the combination of two plate sections and a cover superimposed one on another and rivets set in holes formed in the bottoms of conical offsets which are stamped in the two plate sections and in the cover and are nested together the projections on one plate section within the depressions of the second plate section and the projections of the second plate section within the depressions in the cover, the heads formed on the ends of the rivets being countersunk in the depressions of the first plate section.

2. A riveted joint for metallic plates, sheets, and the like, comprising two overlapped plate sections having formed therein two rows of offsets projecting the offsets of one row to one side and the offsets of the other row to the other side of the two plates and nested together the projections of the inner row of offsets of each plate within the depressions of the outer row of offsets of the other plate, rivet holes in the bottoms of said offsets, and rivets set in said holes.

CHARLES WARD HALL.
